GARMENT HANGER

Siegfried Behr, Flushing, N. Y.

Application January 16, 1946, Serial No. 641,481

2 Claims. (Cl. 223—88)

1

My invention relates generally to improvements in garment hangers and more particularly to a hanger which may be utilized not only as a hanger for coats but also may be used for hanging many other garments including trousers and ladies' garments having shoulder straps.

A primary object of my invention is to provide such a hanger made entirely of plastic material.

Another object is to provide a hanger of this character with broad rounded and arched shoulder bars serving to properly engage and support a garment in a natural condition.

Another object is to provide means for supporting the sleeves of a coat in a natural condition.

Another object is to provide a hanger of this kind that will support both a coat and a lady's slip or other garment having shoulder straps.

Still another object is to provide shoulder bars with means for preventing the garment from slipping or becoming displaced thereon.

Yet another object is to provide such a hanger with a trousers supporting bar of substantial thickness and having a smooth rounded and arched trousers engaging surface for properly supporting the trousers without creasing or marking the same and for providing additional strength and rigidity to the hanger.

A further object is to provide the trousers engaging surface with means for preventing the slipping or displacement of the trousers thereon.

Still another object is to provide a hanger of this kind that is simple in construction, strong and durable, inexpensive to manufacture and is well adapted for the purposes intended.

Fig. 1 is a side view of a garment hanger embodying one form of my invention.

Fig. 2 is a top plan view thereof.

Fig. 3 is a sectional view taken on the plane of the line 3—3 of Fig. 1.

Fig. 4 is a view similar to Fig. 1 showing a trousers supporting bar in position thereon.

Fig. 5 is an enlarged sectional view taken on the plane of the line 5—5 of Fig. 4.

Fig. 6 is an enlarged sectional view taken on the plane of the line 6—6 of Fig. 5.

As shown my improved hanger is substantially triangular in shape and is formed entirely of any suitable plastic material. The body portion includes an upper central or neck portion 10 which forms a base for an integral hook member 11 projecting upwardly therefrom for supporting the hanger on any suitable support.

Suitably secured to the central or neck portion 10 are elongated shoulder bars 12, each bar con-

2

sisting of a rear portion 12' extending outwardly and downwardly of the neck portion and substantially in the plane thereof and a curved portion 13 joining the outer end of portion 12 with an integral laterally curved front shoulder 14. Each bar 12 is thus substantially oval-shaped in plan as seen in Fig. 2, with the front shoulder bar 14 and the curved end portion 13 positioned on a plane offset from the plane of the neck or central portion 10 for supporting the shoulder and sleeve of a coat or the like in a natural condition. The upper surfaces of shoulder bars 12 and 14 are provided with protuberances 15 to reduce the tendency of the garment to slip or become displaced thereon. Depending from the outer curved portion 13 is an integral bar 16 terminating at its lower end in an inwardly extending horizontal lug 17. An integral stud 18 extends upwardly from each of the lugs.

20 In Fig. 4, an elongated trousers supporting bar 19 is shown on the studs 18 and extending between the end portions 16. The bar is provided with openings 20 adjacent its ends for insertion over the studs 18. This bar is substantially T-shaped in cross-section, the upper surface 21 thereof being curved and broad whereby the trousers or the like is provided with a broad supporting surface for reducing the tendency to crease or mark the trousers to a minimum.

25 The upper curved surface of the bar 19 is formed with transverse grooves 22 to reduce the tendency of the trousers or other garment to slip or become displaced on the bar.

30 The spread apart and open shoulder bars 12 form a broad support for the shoulder portions and sleeves of a coat or the like and with the curved portion of the front portion permit the coat to hang in a natural condition.

35 The straps of a lady's slip or other garment 40 can be easily slipped over the studs 18 so that the slip can be hung in a natural condition.

40 When it is desired to convert the hanger from a slip supporting hanger to a trousers supporting hanger it is only necessary to mount the bar 19 45 on the studs 18.

I claim:

45 1. A plastic garment hanger comprising a body having a flat central portion with tapered edges for supporting and engaging the neck of a coat or 50 the like, an integral hook portion extending upwardly from said central portion, shoulder bars supported by said central portion, each bar consisting of a rear portion sloping outwardly and downwardly from said central portion and positioned substantially in the plane of the central

portion, said rear portion terminating in an integral portion curved forwardly therefrom, and a front portion formed integrally with said curved portion, said curved and front portions being disposed on a plane offset from the plane of the central portion whereby said bar is substantially oval-shaped in plan for supporting the shoulder and sleeve of a coat or the like in natural condition, an integral bar depending from each outer curved portion and terminating in an inwardly extending horizontal lug portion, an integral stud on each lug portion extending upwardly therefrom and a transverse bar detachably mounted on said studs for supporting a trousers or the like.

2. A plastic garment hanger comprising a body having a flat central portion with tapered edges for supporting and engaging the neck of a coat or the like, an integral hook portion extending upwardly from said central portion, shoulder bars supported by said central portion, each bar consisting of a rear portion sloping outwardly and downwardly from said central portion and positioned substantially in the plane of the central portion, said rear portion terminating in an integral portion curved forwardly therefrom, and a front portion formed integrally with said curved portion, said curved and front portions being

disposed on a plane offset from the plane of the central portion whereby said bar is substantially oval-shaped in plan for supporting the shoulder and sleeve of a coat or the like in natural condition, an integral bar depending from each outer curved portion and terminating in an inwardly extending horizontal lug portion, an integral stud on each lug portion extending upwardly therefrom and a transverse bar detachably mounted

10 on said studs for supporting a trousers or the like, said shoulder bars having protuberances on their upper surfaces and said transverse bar having grooves in its upper surface to prevent slippage and displacement of a garment supported thereby.
